of Delaware

Application December 5, 1928, Serial No. 323,809

1 Claim. (Cl. 250—8)

This invention relates to radio communication, and more particularly to a method and means for reducing the effect of fading when communicating on short waves.

To overcome the effect of fading when communicating on short waves is the primary object of my invention, and to this end I propose a frequency diversity method, which includes the transmission and reception of the same signal on several short wave carriers having only slightly different frequencies. It is not feasible to employ widely different frequencies because the diurnal transmission characteristics then will differ, and during much of the day if one of the frequencies comes through the others will not, so that instead of having a diversity system there will be only one channel in operation. Furthermore it is far preferable to utilize slightly different high frequencies in accordance with my invention because less space in the available frequency spectrum is needed for each channel. I propose, for example, to use a difference of the order of magnitude of that between 16 and 16½ meters as a maximum, and, in the case of code signals, I find that it is satisfactory to use a difference as slight as an audible frequency, say 2 or 3 thousand cycles per second. In this manner the general transmission characteristics are kept alike, but the instantaneous fading characteristics may differ widely.

I find that not only does the fading at any instant of two waves of slightly different high frequency continually vary, but, consistently therewith, their relative phase also continually varies relative to the normal variation due to frequency difference. It therefore would be impossible to combine the radio frequency energies directly together, even if they were of the same frequency.

It therefore also is impossible to combine equal intermediate frequencies together, after beating each of the received frequencies with a different local oscillator frequency such that the intermediate frequencies are equal, because the relative phase of the intermediate frequency energies fluctuate just like that of the incoming radio frequency energies, for if of two beating waves one is kept constant in phase, while the other is varied in phase, their beat is equally varied in phase. Now in accordance with my invention I overcome these difficulties by first rectifying the received energies, and combining them only after rectification, so that the combination is substantially independent of radio frequency phase.

In the case of code communication I may employ two transmitters of different frequency, and key them simultaneously. In such case both

transmitters transmit during marking periods, and not during spacing periods. As an alternative the transmitters may be keyed so that one is transmitting during marking periods, and not during spacing periods, while the other transmits during spacing periods, and not during marking periods. This possesses the advantage of making it possible to employ a single transmitter and to slightly detune the transmitter with the keying means, in order to obtain a back wave for the spacing periods.

At the receiver the radiated energies are collected, amplified separately or together, but, separately rectified, and then the marking energy is utilized to actuate a translating device in one sense, and the spacing energy is used to actuate the same translating device in the opposite sense, so that both and also either of the marking and spacing energies alone will produce a readable signal. To accomplish this effect in a very simple manner I reverse the phase of one of the rectified energies, preferably by putting the energy through a three electrode tube, and then combine the rectified energies in additive phase and apply the combined energy to a single translating device.

My invention is described more particularly in the following specification, which is accompanied by drawings in which Figure 1 is a code communication system arranged for simultaneous transmission of the marking periods; Figure 2 is a modification applicable to signal modulation by speech or other speech-simulating signals; Figure 3 is an arrangement for alternate transmission of marking and spacing waves; Figure 4 is a section of tape explanatory of the operation of the arrangement shown in Fig. 3; Figure 5 is a system employing a single transmitter arranged for keying with a back wave, and a preferred form of receiver; and Figure 6 is a portion of recording tape explanatory of the operation of the receiver shown in Figure 5.

Referring to Figure 1 there are a pair of transmitters 2 and 4, each tuned to slightly different high frequencies, and each coupled to an antenna 6 and 8. Both transmitters are simultaneously keyed by a single keying means, which arrangement is schematically indicated by the key 10, connected in parallel to both of the transmitters. The details of the keying connections are immaterial, and may be of any conventional type, such as those which establish a high negative or blocking bias on the control electrode of one of the tubes in the transmitter.

The receiver cooperating with the transmitter 55

shown in Figure 1 may be of simple form, comprising the antennas 12 and 14, and the amplifiers 16 and 18, each tuned to the frequency of one of the radiated waves. It should be understood that the amplifiers 16 and 18 may include auto-dyne or heterodyne stages, so that part or all of the amplification may be performed at an intermediate instead of at the original radio frequency. The amplified energies are fed to separate detectors 20 and 22, here illustrated as full wave rectifiers, the output from which may be amplified in amplifier tubes 24 and 26, and then combined in a common relay 28, which, in the case of a remotely located translating device 30, may be used to key a tone generator 32 in order to transmit a tone signal on the land line 34 in accordance with the received code signal.

If it is desired to transmit speech, or other speech-simulating signals, such as modulation for multiplex code or picture work, a very similar arrangement may be employed, indicated in Figure 2, in which the transmitters 2 and 4 are modulated, rather than keyed, in any conventional manner, by a microphone or other source of modulating energy 36. The radiated energy is collected on antennas 12 and 14, amplified in amplifiers 16 and 18, rectified in rectifiers 20 and 22, to obtain the modulation energy, which then may be amplified in amplifier tubes 24 and 26, the outputs from which are combined in a single impedance 38, coupled to an amplifying tube 40, the anode circuit energy of which is fed, through a transformer 42, to any suitable translating device, here exemplified by a loud speaker 44. The two carriers used in this scheme should differ sufficiently so that the side bands will not overlap, but this is readily provided with the short waves here considered.

In the case of code communication I consider it preferable to so key the transmitters that one transmits during the marking periods, while the other transmits during the spacing periods, and such arrangement has been illustrated in Figure 3. Referring to this figure it will be seen that the transmitters 52, and 54, instead of being coupled to separate antennas, as in Figure 1, are coupled to a single antenna 56, but in this case the keying means 60 is arranged, as shown, to affect the transmitters alternately, rather than simultaneously. The receiver, instead of employing separate antennas, also has a single antenna 62, coupled to amplifiers 66 and 68, which in turn lead to rectifiers 70 and 72, the outputs from which may be amplified in amplifier tubes 74 and 76. However, the energies cannot then be directly combined together, as in Figure 1, for they then act in the same direction and no useful effect on the recorder would be obtained inasmuch as they would add up to a constant value, and yield no signal at all. To obtain a signal these energies must be combined differentially, and this has been indicated by the zero center differential relay 80, which is presumed to control a spring centered contacting arm which closes the circuit of the common line 81 with either the positively charged line 82, or the negatively charged line 84, according to which of the receivers is being energized by the transmitter at that instant. The lines 82 and 84 may extend to a remote translating device 86, which is so arranged that it is actuated in one sense by the positive current, and in opposite sense by the negative current, so that relative to a mean zero line, both and also either of the marking and spacing energies will produce a readable signal.

This may be explained in connection with Figure 4, indicating fragmentary portions of a recording tape obtained from the translator 86 in Figure 3. Referring to Figure 4 it will be seen that relative to a mean zero line, when one of the signalling energies, say the spacing energy, fades, and the marking energy does not, a tape will be obtained showing the desired signal above the zero line, as is indicated at 90. If, on the other hand, the marking energy should fade, while the spacing energy does not, a signal will be obtained below the zero line, but readable with respect to its own lower base line, as is indicated at 92. However, should neither fade, a signal of amplified strength will be obtained, ranging between the extremes of the negative flow produced by the spacing wave, and the positive flow produced by the marking wave, as is indicated at 94. Except in the event of simultaneous fading of both the marking and spacing energies, a readable signal will always be produced.

In Figure 3 the transmission system utilizes separate transmitters, but one is worked while the other is not. Only one being worked at a time suggests the possibility of using a single transmitter keyed with a back wave, and such an arrangement is shown in Figure 5. Referring to that figure there is a tube 100, the anode to cathode and control electrode to cathode circuits of which are regeneratively coupled by the coils 102 and 104, which are tuned by a tuning condenser 106. Direct anode and control electrode bias potentials are applied through the leads 108 and 110 to either side of the blocking condensers 112 and 114. The output of this oscillator may be amplified in any suitable power amplifier 116, and radiated over an antenna system 118. The oscillator is so keyed as to change its transmission frequency slightly. Two simple ways to do this have been indicated, in one of which a key 120 is used to short circuit a portion of the inductance of the resonant circuit, and in the other of which a key 122 is used to vary the spacing of a small condenser 124, which is connected in parallel with the main tuning condenser 106. By these or any other suitable frequency varying schemes a single transmitter may be employed in place of the two transmitters indicated in Figure 3.

The receiver shown in Figure 5 comprises an antenna 130, the energy collected by which is amplified in a radio frequency amplifier 132, and then heterodyned with energy from a local oscillator 134, in a heterodyne detector 136, to obtain intermediate frequency energy. This is readily separated into marking and spacing energies, by the high pass filter 138 and the low pass filter 140. The filtered energies are also respectively amplified in intermediate frequency amplifiers 142 and 144. The amplifier outputs are rectified in suitable rectifiers 146 and 148, the rectified currents from which are passed through low pass filter sections 150 and 152, which serve to by-pass the radio frequency components of the rectified energy, and to steady the rectified signal energies. One of the rectified energies is reversed in phase, preferably by passing it through a three electrode tube 154, coupled by a suitable coupling resistance 156, and the anode circuit of the tube 154 is connected to the anode circuit of the rectifier 148, as shown. The anode of the tube 154 is polarized by a suitable source of direct anode potential 158. The control electrode of the tube 154 is biased from a bias battery 160, in cooperation with a potentiometer resistance 162, and the magnitude of the bias potential is so adjusted that it will be 75

overcome or made sufficiently negative by incoming signal energy to stop anode current from flowing. With this adjustment the pen of the translating device 164 normally will remain at a value above the zero axis, assuming no keying, because of the steady anode current from the source 158. Should one of the signals, say the marking signal, alone reach the receiver, and it be amplified and rectified in the units 144 and 148, the resulting rectified current will add to the steady anode current from the source 158, and a readable signal will be obtained above the normal base. This has been indicated at 170 in Figure 6, in which the dotted line shows the normal position of the pen. Should the marking signal fade, and the spacing signal alone reach the receiver, it will serve to negatively bias the tube 154, and so decrease its anode current to zero, resulting in a readable signal such as has been indicated at 172 in Figure 6. If both signals are received without fading, a signal of double amplitude is obtained, as is indicated at 174 in Figure 6.

It should be understood that either of the transmitters indicated in Figures 3 and 5 may be used 25 with either of the receivers shown in Figures 3 and 5. It should also be understood that in any of the receivers the amplifiers which precede the rectifiers may include separate or combined heterodyne means followed by intermediate frequency amplifiers. In code work the intermediate frequency may be as low as an audio frequency. Also, any of the rectifiers may be equipped with

low pass filters, such as has been indicated in Figure 5. The single antenna shown in Figure 3 may be used in connection with the other arrangements illustrated in Figures 1 and 2, instead of separate antennas, owing to the closeness of the two carrier frequencies. Full wave rectifiers are not essential. More than two frequencies may be employed, if desired, particularly in the arrangements shown in Figures 1 and 2.

I claim:

An arrangement for reducing fading when transmitting code signals on short waves including a transmission system comprising a short wave transmitter, keying means for slightly changing the frequency of transmission to distinguish between marking and spacing periods, and means to radiate the marking and spacing energies alternately, and a receiving system comprising means to collect the radiated energies, separate electron emission tube amplifiers for the marking and spacing energies, separate rectifiers coupled to each of said amplifiers, a three electrode tube coupled to the output circuit of one of the rectifiers for reversing the phase of the rectified energy, means coupling the anode circuit 25 of the three electrode tube with the output circuit of the other rectifier so as to combine the marking and spacing energies in additive phase, and a translating device responsive to the combined energy.
